UNITED STATES PATENT OFFICE.

RUSSELL AVERY, OF SAUSALITO, CALIFORNIA, ASSIGNOR TO AVERY DRILL COMPANY, OF SAN FRANCISCO, CALIFORNIA, A CORPORATION OF CALIFORNIA.

ROCK-DRILL.

SPECIFICATION forming part of Letters Patent No. 709,191, dated September 16, 1902.

Application filed December 21, 1901. Serial No. 86,850. (No model.)

To all whom it may concern:

Be it known that I, RUSSELL AVERY, a citizen of the United States, residing at Sausalito, county of Marin, State of California, have invented an Improvement in Rock-Drills; and I hereby declare the following to be a full, clear, and exact description of the same.

My invention relates to an apparatus for drilling rock and the like; and it consists in improvements in mechanism for carrying, turning, and reciprocating the drill in conjunction with a flexible connection between this mechanism and means by which the said connection is reciprocated and the mechanism is actuated between the blows delivered upon the drill or its actuating-bar.

My invention also comprises details of construction, which will be more fully explained by reference to the accompanying drawings, 20 in which—

Figure 1 is a general perspective exterior view. Fig. 2 is a plan and part section with the top of the case removed. Fig. 3 is a section through $x-x$ of Fig. 2. Fig. 4 is a section 25 through $y-y$ of Fig. 2. Fig. 5 is a section through $v-v$ of Fig. 2. Fig. 6 is a transverse section through $z-z$ of Fig. 2.

The object of this invention is to provide an apparatus which is easily and accurately 30 adjustable with the drill so directed as to make the hole in any desired direction, to enable the drill to be withdrawn, moved out of line of the hole, and restored to its proper direction at any time when the drill-hole needs 35 inspection or attention.

It has for its further object a simple mechanism connected by a flexible cord with the person of the one who wields the hammer to strike the drill, so that at each backward 40 swing preparatory to a blow the drill will be slightly raised and turned so as to rest in the new position for each blow, and this work is all effected by a single operation instead of its being necessary to have any person to 45 hold and turn the drill.

As here illustrated, A is a case of any suitable or desired form and dimension which will be sufficient to contain the operative mechanism. I have shown this case as closed 50 at the top by a removable cover 2, so that while it is kept clean and tight under ordinary con-

ditions the cover may be removed for inspection or any work required to the interior mechanism.

The drill 3 has its upper end or head secured in any suitable or well-known socket 4, and this socket is carried by a bar 5, which extends through the casing A, so that a blow may be struck upon the opposite end and will be communicated directly to the drill, 55 which is thus advanced in the drill-hole. Through the bar 5 the drill is slightly retracted after each blow, so as to allow it to be turned, as is customary, to prevent the drill sticking and do the most effective work. This 60 retracting and turning of the drill is effected in the following manner: Upon opposite sides the bar 5 has teeth or notches, as at 6, and these teeth or notches are engaged by spring-pressed slidable pawls 7, these pawls 65 being located in a pawl-carrier 8, in which they are slidable. The points of the pawls are held against the teeth 6 of the bar by the pressure of light springs 9, which are sufficient to retain them in contact with the teeth, but 70 which will yield easily to allow the drill to advance when blows are struck upon the bar, and as each of the teeth or notches 6 pass the pawls the latter will drop back into the following notches, and thus keep the drill to its 75 work. The pawl-carrier 8 is normally pressed forward by a coiled spring 10, which presses 80 against a flange upon its rear end. Within this pawl-carrier are fulcrumed levers 11, which are in shape of bell-crank levers, hav- 85 ing the fulcrumed pins at the angle, the longer arms 11 extending radially outward from the pin and the shorter arms 11^a entering holes 12 in the pawls 7, as plainly shown in Figs. 2 and 5. These levers act to force the pawls 90 tightly against the bar, so as to clamp it at the instant when the levers and the pawl-carrier are moved backwardly by a mechanism to be hereinafter described, and when they are thus clamped and moved backwardly they 95 withdraw the bar and the drill, so that the latter is clear of the bottom of the hole and can then be turned by the mechanism to be described. The turning is effected as follows: The rope or flexible cord 13 has one end connected with the operator (not here shown) 100 and the other end with the outer end of a le-

ver-arm 14. This lever-arm has its inner end fixed to a shaft 15, and this shaft carries a cam 16, which in the present case is shown to be rectangular in shape and having projecting ribs 17 upon its angles, which ribs contact with the flange of a sleeve 18, which is loosely slideable upon the bar 5. This flange is normally separated from the pawl-carrier 8 by light spiral springs 19, so that the ends 5 of the levers which engage the pawls 7 will normally project into the space between the flange 18 and the pawl-carrier. When the cam 16 is turned by the movement of the shaft 15, it presses the flange 18 toward the 10 pawl-carrier, and acting upon the projecting arms 11 of the pawls it causes the arms 11^a to force the pawls against the teeth of the bar 5, so as to firmly grip the bar, and the further turning of the cam presses both the disk 18 and the pawl-carrier 8 backwardly against the tension of the spring 10. This retracts the bar 5 and the drill 3, which is then turned by the continued turning movement of the shaft 15, actuated by the movement of the 15 lever 14. The movement of the cam 16 is effected by teeth 20, formed around the periphery of the shaft, so that they will engage with spring-pressed pawl-pins 21, which are slideable in the cam 16 and are normally held 20 pressing against the surface of the shaft by springs, as at 22. Thus when the shaft is turned the tooth 20, engaging with the pawl 21, will cause the cam to turn, and its angle acting against the flange 18 first compresses 25 the spring 19 and, through the levers 11, causes the pawl 7 to grip and retract the bar 5. When the highest point of the cam passes and releases the flange 18, the parts are returned to their normal position, and the lever 30 30 40 45 50 55 60 65 70 75 80 85 90 95 100 105 110 115 120 125 5, thus allowing the bar to be moved back freely ready for a new advance. If the bar and drill are to be removed from the case, it is done by pulling out toward the forward end.

5 The case A has a transverse sleeve 38 across the lower part, and this is turnable within an exterior clamp 39. The sleeve 38 is slidable transversely upon a square or other guiding-bar 40, which is rigidly fixed with relation to the hole to be drilled. The case A can be moved by sliding upon the transverse bar 40, either to bring it in line with the drill-hole or to take it out of line when desired. When in line with the drill-hole, the casing may be turned about the sleeve 38, and when the proper direction is obtained the clamp 39 is closed by a nut and screw, so as to firmly grip the sleeve, which latter may also be secured to the bar 40 by a set-screw or other device, and the parts will then be firmly held as long as desired. If access to the drill-hole is required for the purpose of cleaning or for other reason, the parts may be retracted and removed to one side without disengaging the supporting-bar 40.

The drill-bar may be continuous and integral with the drill itself or it may be separate with a connecting-socket. The teeth or serrations may be made in any manner to insure 30 the proper engagement of the pawls or gripping devices.

I have heretofore described the mechanism as operated by a flexible cord, which may be connected so as to be actuated by the movements of a single person, who is also the striker, but when increased speed is required there may be a plurality of strikers whose blows are delivered alternately, and a third person whose office is to reciprocate the cord 40 between the blows, either by direct pull or through the intervention of a crank or other mechanical expedient.

Having thus described my invention, what I claim, and desire to secure by Letters Patent, is—

1. The combination in a manually-operated drill, of a casing and a bevel-gear located within the casing through which the drill-bar is guided and slidable, a second bevel-gear 50 mounted upon a transverse shaft engaging the first-named gear, a lever-arm exterior to the casing with connections whereby the gears and drill may be turned by the movement of the lever, a cord having one end connected with the outer end of the lever and the opposite end with the person of the hammer-wielder whereby the drill is turned at each backward swing of the body, and a spring by which the lever is returned to its normal position when released.

2. The combination in a drill of a casing and a bevel-gear through which the drill-bar is guided and slidable, a transverse shaft carrying a bevel-gear engaging the first-named 65 and a spur-gear upon the outer end, a second transverse shaft having a spur-gear upon its outer end engaging the spur-gear of the

first-named shaft, an exterior lever, a cord connecting its outer end with a means to reciprocate it, means connecting the inner end 70 of the lever with the second shaft whereby said shaft is turned by a forward movement of the lever, and a spring by which the lever and shaft are returned to their normal position when released. 75

3. The combination in a drill of a casing, a drill-bar guided and movable therethrough, bevel-gears through which movement is transmitted to turn the drill, a transverse shaft in the casing, a lever-arm fixed to the outer end 80 of the shaft through which movement is transmitted to turn the shaft, a clamping device adapted to grip the drill-bar, a cam carried by and turnable with the shaft by which said clamp grips and retracts the drill-bar at the 85 first part of the turning of the shaft and gears and pawl-and-ratchet mechanism by which the movement of the shaft is subsequently transmitted to turn the drill.

4. The combination in a drill of a casing 90 through which the drill-bar is guided and slidable, bevel-gears by which the drill is turnable, a clamping mechanism by which the drill-bar is engaged and retracted previous to turning, said mechanism consisting of a transverse shaft carrying the clamp-actuating cam, a lever fixed upon the outer end of the shaft through which movement is transmitted, a gear and internal ratchet loosely turnable upon the shaft, a spring-pressed pawl-pin carried by the lever and movable therewith so that the drill is retracted before the pawl engages the ratchet, and a second gear through which motion is transmitted from the first one to turn the drill. 105

5. The combination in a drill of a casing, a drill-bar guided and slidable therethrough, means for retracting the drill previous to turning, consisting of teeth or serrations upon the drill-bar, pawls adapted to engage said teeth, means by which said pawls are forced into engagement consisting of a revoluble cam and disk through which movement is transmitted, a shaft by which the cam is carried, a lever-arm fixed to the outer end of the shaft, 110 connections between said lever-arm whereby it is moved, and the shaft and cam partially rotated, and the spring connected with the shaft by which the parts are returned to their normal position. 115

6. The combination in a drill of a casing, a drill the bar of which is guided and slidable therethrough, teeth or serrations formed upon the drill-bar, pawls and a carrier within which they are movable, levers engaging said pawls, 120 a cam mounted upon a shaft and turnable therewith, a disk slidable upon the drill-bar against which disk the cam acts and through which the pawl-levers are actuated, and the pawl caused to grip the drill-bar and the latter is retracted. 125

7. The combination in a drill of a casing, a drill, the bar of which is guided and slidable within the casing, a gripping mechanism con-

sisting of pawls and levers by which they are caused to grip the drill-bar, a cam mounted upon a revoluble shaft through which cam the movement is transmitted to actuate the 5 pawl-levers, a shaft through which motion is transmitted to the cam, said shaft having ratchet-teeth and turnable loosely in one direction within the cam, a spring-pressed pawl carried by the cam and engaged by the teeth 10 of the shaft when turned to advance the cam, and a spring by which the shaft is turned backwardly when impelling pressure is removed.

8. In a drill, a casing, a drill, the bar of 15 which is guided and slidable therein, gripping pawls and levers by which they are forced into contact with the drill-bar, a cam mounted upon a transverse revoluble shaft, and by which the pawl-levers are actuated, 20 pawl-and-ratchet connections between the cam and the shaft upon which it is mounted whereby the cam is advanced when the shaft is turned in one direction and a spring by which the shaft is returned within the cam 25 when the turning pressure is relieved.

9. In a drill, a casing, a drill the bar of which is guided and slidable within the casing, mechanism by which the drill-bar is first retracted and subsequently turned, said 30 mechanism consisting of pawls and a cam by which the pawls are caused to grip and retract the drill-bar, a shaft upon which the cam is carried, a spur-gear loosely mounted upon the shaft having a ratchet-wheel turnable in unison with it, a lever-arm fixed upon the shaft through which power is transmitted to turn it, a spring-pressed pawl carried by 35 the lever and normally out of operative contact with the ratchet-teeth whereby the shaft 40 and cam are moved before the pawl engages the ratchet, a second spur-gear engaged by the first mounted upon a shaft within the casing, and bevel-gears through which motion is transmitted to turn the drill-bar when 45 the pawl has engaged with the ratchet, and a spring surrounding the first-named shaft whereby the shaft and parts carried thereby are returned to their normal position after the pull upon the lever has been released.

50 10. In a drill, a casing, a drill the bar of which is guided and slidable therein, an oscillating lever and a transverse shaft to which

it is fixed, a cam and gripping-pawls actuated thereby to first retract the drill, spur and bevel gears carried thereby through which 55 motion is transmitted from the shaft to subsequently turn the drill and a spring acting against the pawl-carriers whereby the drill is forced against the surface to be operated on when released from its pawls. 60

11. In a drill, the casing, a drill, the bar of which is guided and slidable within the casing, gripping mechanism by which the drill-bar is retracted, and bevel-gears by which it is subsequently turned, a lever, a shaft to 65 which it is connected, and a cam and pawl-and-ratchet mechanism actuated by said shaft to retract and turn the drill successively, a sleeve extending through the rear of the casing and connected with the pawl-carrier, a 70 second sleeve surrounding the first one and itself movable through the end of the casing, a spiral spring surrounding the first sleeve, with one end pressing against the pawl-carrier and the other against the inner end of the 75 outer sleeve, an annular groove in the casing, a lug carried by the outer sleeve, a channel by which it may be moved to engage the groove or the face of the sleeve in front thereof to regulate the tension of the spring. 80

12. The combination in a drill of a casing and a bevel-gear through which the drill-bar is guided and slidable, a transverse shaft carrying a bevel-gear engaging the first-named, and a spur-gear upon the outer end, a second 85 transverse shaft having a spur-gear upon its outer end engaging the spur-gear of the first-named shaft, an exterior lever, a cord, one end of which is connected to the outer end of the lever, and the other end with a means by 90 which it may be periodically reciprocated between the drill-impelling blows, means connecting the inner end of the lever with the second shaft, whereby said shaft is turned by a forward movement of the lever, and a 95 spring by which the lever and shaft are returned to their normal position when released.

In witness whereof I have hereunto set my hand.

RUSSELL AVERY.
